UNITED STATES PATENT OFFICE

JAMES KILLIUS AND CHARLES H. DE FREHN, OF JOHNSTOWN, PENNSYLVANIA

CUPBOARD DESK

Application filed November 5, 1931. Serial No. 573,180.

By way of explanation, it may be stated that there is in common use, a school desk comprising a frame, a forwardly-extended seat pivotally mounted on the frame, a back 5 for the seat, carried by the frame, and a rearwardly-projecting top mounted on the frame, the top of one desk being accessible to a person occupying the seat of the desk next in the rear. When a school room is equipped 10 with a plurality of desks, constructed and arranged as above set forth, there is, at the front of the room, a transverse line of seats which are of no particular use, since there is no desk in front of them. One object of the 15 present invention, therefore, is to provide a means whereby the front row of seats can be taken off, and be replaced by cupboards or cabinets, which will afford convenient storage space along the front line of desks in a 20 school room.

Another object of the invention is to provide novel means for mounting and controlling the slidable front of the cabinet or cupboard.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes

in the precise embodiment of the invention herein disclosed, may be made within the scope of what is claimed, without departing from the spirit of the invention.

In the accompanying drawings:—

Figure 1 shows in side elevation, a school desk to which the device forming the subject matter of this application has been applied;

Figure 2 is a front elevation of the structure shown in Figure 1;

Figure 3 is a vertical transverse section;

Figure 4 is an end view showing a portion of the flexible front of the cabinet;

Figure 5 is a fragmental vertical section, 50 wherein the latch appears;

Figure 6 is a fragmental horizontal section;

Figure 7 is an enlarged section on the line 7—7 of Figure 2.

In Figures 1, 2 and 3, there is shown a support for the device hereinafter referred to as the cabinet, the support being a school desk 1 of ordinary construction, comprising metal frames 2 having outstanding portions 3 provided with hubs 4 on which the seat (not shown) is pivotally mounted, at the places indicated for the purposes of the present discussion by the elements 14 although those elements are not seat supports, in the device described, shown and claimed. The frames 2 carry a back 5 for the seat, and the frames support a top 6, the construction being such that the pupil occupying the seat of the desk in the rear can use the top 6 of the desk shown.

As has been stated hereinbefore, the front seats in the school room are of no use, and in the present invention, they are replaced by cabinets 7.

The cabinet 7 embodies a back 8, which need not be curved to fit accurately against the back 5 of the desk, side walls 9, a top 10 abutting at its rear edge against the back 5, and a bottom 11. Through the side walls 9 pass securing elements 14, such as screws, the securing elements entering the hubs 4 of the parts 3 of the frames 2, to support the cabinet 7 between the said parts 3 of the frames, as shown in Figure 2. Although the elements 14 have been referred to as securing elements, they need not necessarily clamp the cabinet 7 tightly in place. The securing elements 14 may act as pivot elements, because they are located near enough to the front of the cabinet 7, so that the cabinet 7 will tend to gravitate backwardly, the rear edge of the top 10 of the cabinet resting against the back 5 of the desk, and the cabinet retaining the substantially vertical position of Figure 3, no matter how heavy the load in the cabinet may be. Gravity need not be relied upon alone to keep the cabinet 7 from tilting forwardly: it may be connected detachably to the back 5 in any suitable way, for instance by hooks 12. The cabinet 7 may be tilted forwardly from 100

the position of Figure 1, if the hooks 12 are released, when it is desired to brush the dirt out of the cabinet. A shelf 15 is located in the cabinet 7, and is placed about midway 5 between the top 10 and the bottom 11.

The cabinet 7 has a flexible front 16, made up of slats 17, 20, and 21, the slat 20 being the uppermost slat, and the slat 21 being the lowermost slat. The slats 17, 20, and 21 are 10 secured, by gluing or otherwise, to a flexible backing strip 18, as is common in the art. At their ends, the slats 20 and 21 of the flexible front 16 have reduced tenons 19 of the same thickness as the intermediate slats 17, 15 so that both the tenons 19 and the ends of the slats 17 can slide in vertical guide grooves 24, formed in the inner surfaces of the side walls 9 of the cabinet, the guide grooves being open at both their upper and their lower ends. 20 On the left hand end of the uppermost slat 20 of Figures 7 and 2 there is an outwardly extended projection 22, such as a pin; and on the right hand end of the lowermost slat 21 of Figure 2 there is a corresponding projection 25 or pin 23.

A stop 26, which may be a screw, is mounted in one of the side walls 9, and extends into the path of the projection 22 on the end of the uppermost slat 20, a stop 27, on the opposite side wall 9, bearing the same relation to the projection 23 on the lowermost slat 21. Because the slats 20 and 21 are thicker than the slats 17, the projections 22 and 23 can be located in front of the side walls 9 (Figure 35 7) and it is not necessary to groove or alter the side walls 9 in any way for the accommodation of the projections 22 and 23. The stop 26 is located far enough below the shelf 15, so that when the flexible front 16 is slid 40 downwardly until the projection 22 on the uppermost slat 20 has engaged the stop 26, the upper edge of the uppermost slat 20 will be flush with, or a little below, the upper surface of the shelf 15, thereby opening completely 45 the upper compartment 29 (Figure 3) which exists above the shelf 15. In a similar way, when the flexible front 16 is pushed upwardly, until the projection 23 on the lowermost slat 21 engages the stop 27, the lower 50 edge of the lowermost slat 21 will be flush with, or a little above, the lower surface of the shelf 15, thereby opening completely, the lower compartment 28, which exists below the shelf 15. When the flexible front 16 is raised, 55 to open the lower compartment 28, the flexible front 16 folds backwardly and is supported on the top 10 of the cabinet 7, the guide grooves 24 being open at their upper ends. When the flexible front 16 is lowered, 60 to open the upper compartment 29, the front simply slides downwardly in the guide grooves 24, the said grooves open at their lower ends.

The uppermost slat 20 of the flexible front 65 16 carries a latch 30, of any desired construc-

tion, and under the control of an operator, the latch being adapted to engage automatically with a keeper 31 on the forward edge of the top 10 of the cabinet, when the front is moved upwardly or downwardly, the purpose of the latch 30 and the keeper 31 being to hold the front 16 in the closed position of Figure 3.

What is claimed is:—

1. In an article of furniture, horizontally spaced frames, each having a forwardly projecting portion, a back connecting the frames and located above and to the rear of said forwardly projecting portions, a cabinet having its rear part abutting against the back, and means for mounting the lower end of the cabinet detachably on the forwardly projecting portions of the frames, the upper end of the cabinet being exposed, and the space above the upper end of the cabinet being open and unencumbered. 75

2. In an article of furniture, horizontally spaced frames, each having a forwardly projecting portion, a back connecting the frames and located above and to the rear of said forwardly projecting portions, a cabinet having its rear part abutting against the back, and pivot elements connecting the lower end of the cabinet with the forwardly projecting portions of the frames, the pivot elements being located nearer to the front of the cabinet than to the rear part of the cabinet, whereby the cabinet will tend to gravitate rearwardly into abutment with the back, the cabinet being forwardly tilttable on the pivot elements, to promote a cleaning-out of the cabinet, the upper end of the cabinet being exposed, and the space above the upper end of the cabinet being open and unencumbered. 90

3. In an article of furniture, horizontally spaced frames, each having a forwardly projecting portion, a back connecting the frames and located above and to the rear of said forwardly projecting portions, a cabinet having its rear part abutting against the back, and pivot elements connecting the lower end of the cabinet with the forwardly projecting portions of the frames, and a securing device detachably connecting the cabinet with the back, to prevent the cabinet from tilting forwardly on the pivot elements. 100

4. In an article of furniture, a cabinet having substantially vertical guides at its sides, the guides being substantially straight from end to end, a front slidably in the guides, the guides being open at their upper ends, and the front being flexible, whereby when the front is raised, the front can flex backwardly above the extreme top of the cabinet and form the uppermost part thereof, the guides being open at their lower ends, whereby the front may slide downwardly into a depending, exposed position and form the lowermost part of the cabinet, means for supporting the cab- 110 125 130

inet in an elevated position, whereby the front may slide downwardly, as aforesaid, and means for limiting the downward sliding movement of the front.

- 5 5. In an article of furniture, a cabinet having substantially vertical guides at its sides, the guides being substantially straight from end to end, a front slidably in the guides, the guides being open at their upper ends, and the front being flexible, whereby when the front is raised, the front can flex backwardly above the extreme top of the cabinet and form the uppermost part thereof, the guides being open at their lower ends, whereby the front may 10 slide downwardly into a depending, exposed position and form the lowermost part of the cabinet, means for supporting the cabinet in an elevated position, whereby the front may slide downwardly, as aforesaid, a substantially horizontal shelf in the cabinet and dividing the cabinet into an upper compartment and a lower compartment, means for stopping the downward movement of the front, with the upper edge of the front in substantial alignment with the shelf, to open the upper compartment and to close the lower compartment, and means for stopping the upward movement of the front, with the lower 15 edge of the front in substantial alignment with the shelf, to open the lower compartment and to close the upper compartment.

- 20 6. An article of furniture constructed as set forth in claim 5, and further characterized by this: that the stopping means comprise two vertically-spaced projections on the extreme forward edges of the side walls of the cabinet, one projection to each wall, and coacting projections extended laterally from the outer ends of the uppermost and lowermost portions of the front, and located in advance of the extreme forward edges of the side walls of the cabinet.

25 In testimony that we claim the foregoing as our own, we have hereto affixed our signatures.

30 JAMES KILLIUS.

CHARLES H. DE FREHN.
